UNITED STATES PATENT OFFICE

WOODARD COLBY, OF ST. PAUL, MINNESOTA

SAFETY PIN

Application filed August 22, 1929. Serial No. 387,636.

It is my object to provide a safety pin having a prong or penetrating member which is guarded when in free or open position as well as when confined in closed position. As is well known, the so-called safety pins in common use are a constant source of danger and frequently cause serious injury and even death to infants who swallow the pins in open position. The pin of this invention is so constructed that it eliminates this danger and at the same time is stronger than the pins of common type for certain uses.

The invention will be best understood by reference to the accompanying drawings in which Figure 1 is an enlarged side view showing the preferred form of my device in closed or locked position; Fig. 2 is a longitudinal section through the same taken on the line 2--2 of Fig. 1; Fig. 3 is a side view of the pin with the prong in open or unlocked position; Fig. 4 is a side view of an alternate form of the device and Fig. 5 is a fragmentary view showing a further modification.

Suitable spring wire is bent to form a closed loop and a reentrant end of the loop constitutes the prong or penetrating member 6 of the pin. This prong has a pointed, distal end 7 and a bend 8 near its proximal end is arranged to coact with an eye 9 to form a detent for removably securing the pointed end 7 in a keeper 10. Embracing the bend 8, the eye 9 constitutes a sliding connection between longitudinal members 11 and 12 which are joined at their opposite ends by a transverse portion 13.

As best shown in Fig. 2, a keeper 10, secured to the member 13, has a guide plate 14 extending in the plane of the members 11 and 12 and parallel cheek pieces 15 are spaced from the plate 14 and adapted to confine the prong 6 on opposite sides of said plate respectively. Each of the cheek pieces 15, in the preferred form, has a notch 16 adjacent to the member 11 to facilitate insertion of the pointed end 7 into the keeper. The member 12 is formed to normally urge an extremity 16 longitudinally outward from the eye 9 so that when said eye is in engagement with the bend 8, as shown in Fig. 1, the member 12 is held under tension. When the end of the

member 11 adjacent to the eye 9 is pressed inward the member 12 is free to spring to the normal open position shown in Fig. 3 and draws the prong 6 longitudinally and laterally out of the keeper 10. The end of the member 11 adjacent to the eye 9 normally tends to spring outward so as to retain the prong 6 in either the closed position shown in Fig. 1 or the open position shown in Fig. 3, depending upon the position of the eye relative to the bend 8.

In the alternate form of my device shown in Fig. 4, the keeper has a central guide plate 17 and cheek pieces 18, each having an oblique edge 19 beyond which the guide plate 17 projects. The longitudinal member 20 is formed with a coil 21 to increase the resiliency. Further, in this alternate form of pin a bend 22 is provided, similar in construction and function to the bend 8 of the preferred embodiment, and an eye 23 to engage said bend is formed in the adjacent end of a longitudinal member 24. The penetrating member or prong 25 also has a second reentrant bend 26 adapted to limit sliding movement of the eye 23 along the prong when the pin is in open position and affording a stop for material penetrated by the prong 25.

In the modification shown in Fig. 5, the prong 6, bend 8, eye 9 and members 11 and 12 are like those of the preferred construction, but a bead 27 is fixed on the prong 6 to form a stop for the material through which the prong is inserted. When the prong is inserted in a thick body of material this stop, like the bend 26, prevents jamming between the prong 6 and a member 11 which might prevent proper movement of the prong 6 to and from the keeper.

In use, to insert the pin, the proximal end of the prong 6 is grasped together with the adjacent ends of the members 11 and 12 and with said prong in the free position shown in Fig. 3, lateral pressure is applied to the prong sufficient to extend it obliquely to one side of the plane of the members 11 and 12. Now the pointed end of the prong may be inserted into fabric or other material to be held. When the prong has been inserted the pin is closed by longitudinal pressure applied to

the keeper and extremity 16 of the member 12 so that the bend 8 is passed through the eye 9 and the pointed end 7 of the prong 6 is moved longitudinally and laterally into the keeper, as shown in Fig. 1. The prong is held in the keeper by the eye 9 and arrangement of the bend 8 which holds the member 12 under tension. To open the pin, lateral pressure is applied inward upon the member 11 adjacent to the eye 9 to thereby spring the eye over the bend. This allows the member 12 to spring outward and withdraw the prong 6 from the keeper 10.

My improved pin is unusually strong in holding two pieces of material together where tension is applied longitudinally outward on the pieces, in opposite directions. Such tension tends to pull the keeper 10 longitudinally away from the eye 9 or adjacent portion of the prong 6 and is opposed by both longitudinal members 11 and 12 while the prong is pressed into the keeper by the resulting forces.

It will be understood that the cheek pieces 15 and guide plate 14 facilitate the insertion of the prong after it has been sprung out of the plane of the members 11 and 12, to either side. In the event that the pin is closed with the prong 6 outside of the keeper, the notches 16 make it possible to force the prong back into the keeper without releasing the detent, as by moving the eye 9 over and free of the bend 8. The normal tendency of the pointed end 7 of the prong 6 to remain in the plane of the members 11 and 12 and keeper 10 is reinforced by the connection with the member 11 so that in all positions the prong is efficiently guarded.

The operation of the device with the modifications shown in Figs. 4 and 5 is like that of the preferred construction.

While I have illustrated and described certain forms of my device, it is to be understood that I do not limit my invention to such forms and numerous changes may be made within the broad scope of the invention as defined in the appended claims.

Having described my invention what I claim is new and desire to protect by Letters

50 Patent is:

1. A pin comprising, a plurality of longitudinal members, a prong positioned between said members, said prong having a pointed end, a keeper for said pointed end, means for permitting longitudinal movement of said prong to and from said keeper, one of said longitudinal members being adapted to normally withdraw said end longitudinally from said keeper and means for removably securing said end in said keeper.

2. A pin comprising, a plurality of longitudinal members secured together at their ends and extending in substantially the same plane, a prong positioned between said members and substantially in the plane of the

same, said prong having a pointed end adapted to be sprung out of said plane, a keeper near one end of said members adapted to receive and guard said pointed end, one of said longitudinal members being adapted to resiliently withdraw said pointed end from said keeper, and means at the opposite ends of said members for retaining said prong in closed position in said keeper, said pointed end being positioned between said longitudinal members when in open position.

3. A pin comprising, a plurality of longitudinal members formed from spring wire, a prong normally positioned between said members and substantially in the plane of the same, said prong having a pointed end adapted to be sprung out of said plane for insertion in the material to be held, a keeper arranged to receive said pointed end in closed position, one of said members being arranged to normally draw said pointed end longitudinally of said prong out of said keeper, and a detent for retaining said point in said keeper.

4. A pin comprising, a plurality of longitudinal members formed from spring wire, a prong normally positioned between said members and substantially in the plane of the same, said prong having a pointed end adapted to be sprung out of said plane for insertion in the material to be held, a keeper secured to said members adjacent to said pointed end to receive said pointed end in closed position and a detent formed near the opposite ends of said members to secure said pointed end in said keeper.

5. A pin comprising, a loop of spring wire formed with a reentrant prong on one end and with longitudinal members extending in the plane of said prong and on opposite sides thereof, one of said members being slidably secured at one end to the proximal end of said prong, a detent formed in another of said members to engage said slidably end and a keeper supported on the opposite ends of said members to receive the distal end of said prong in one position of the same, said prong being movable to open position between said longitudinal members.

6. A pin comprising, a loop of spring wire formed with a reentrant prong on one end and with longitudinal members extending in the plane of said prong and on opposite sides thereof, a slidably connection between one of said members and the proximal end of said prong, a bend formed in another of said members to engage said slidably connection and a keeper supported on said members to receive the distal end of said prong in one position of the same, said prong being movable to open position between said longitudinal members and being adapted to be sprung laterally out of the plane of said members for insertion in material to be held.

7. A pin comprising, a long and relatively narrow loop formed from spring wire, a re-

entrant prong extending longitudinally within said loop, a keeper secured to said loop to receive an end of said prong in closed position, a member of said loop normally urging said prong to open, guarded position, within said loop and a detent for securing said end of the prong in said keeper against the action of said member.

5 In testimony whereof, I have hereunto signed my name to this specification.
